UNITED STATES PATENT OFFICE

2,407,026

AWNNG

Herman Mashmeyer, Jacksonville, Fla.

Application June 13, 1945, Serial No. 599,243

7 Claims. (Cl. 160—62)

1

My present invention relates to awnings, and has particular reference to an awning composed of a plurality of slidably connected sections adapted to selectively occupy a normally inoperative or non-shading position with the several sections disposed in superimposed relation at the top of the awning; or a normally operative or shading position with the several sections disposed in extended relation; or an intermediate position wherein certain of the sections are superimposed while others are extended. The device of my present invention, like awnings of known construction, is adapted for use on windows, doors, porches and the like, and serves as a means for preventing sun, rain or the like from entering the window or door or impinging upon the porch or other area covered by the awning.

It is an object of my present invention to provide an awning of the so-called "outrigger" type which comprises a suitable frame adapted for attachment to the outside of a window, door or the like, and which frame is adapted to support a plurality of slidably connected, horizontally disposed sections of sheet-like material such as wood, metal, stiffened fabric, plastic or the like, which sections, when in their extended positions, constitute the protective portion of the awning.

It is a further object of my present invention to provide an awning composed of a plurality of slidably connected, horizontally disposed sections adapted to be moved to a normally inoperative or non-shading position wherein the several sections are disposed in superimposed relation, or to a normally operative or shading position wherein the sections are disposed in extended relation, and to associate with such sections a suitable frame or frames adapted for attachment to a door or window frame or other portion of a dwelling to support said sections and to guide the same during their sliding movements.

It is a further object of my present invention to provide an awning of the above mentioned character, and to associate with the same a novel and efficient means for operating the relatively movable sections to move them to and from the desired positions with respect to the supporting frame and to the window, door or the like to which the awning is attached.

It is a still further object of my present invention to provide an awning which may advantageously be made of relatively thin sheet metal or the like, and an awning which is strong and durable, which is cheap and easy to manufacture, which is simple in construction and opera-

2

tion, and which is otherwise highly efficient in the purposes for which designed.

In the accompanying drawings, wherein for the purpose of illustration, I have shown the preferred embodiment of my present invention:

Fig. 1 is a perspective view of the awning showing the same in extended or shading position on the outside of a window frame,

Fig. 2 is a view similar to Fig. 1 but showing the awning in retracted or non-shading position,

Fig. 3 is an enlarged, fragmentary view, partly in section, showing the details of the pin and slot connection between the several sections of the awning,

Fig. 4 is an enlarged, fragmentary view, partly in section, showing the preferred means for mounting the awning frame and the uppermost section of the awning on a window frame or the like,

Fig. 5 is a perspective view similar to Fig. 1 but diagrammatic in so far as the awning and window frame are concerned, and showing in detail an arrangement of pulleys and flexible operating means for moving the slidably connected sections to various positions with respect to the supporting frame,

Figs. 6 and 7 are, respectively, an enlarged fragmentary side view and a perspective view with cover sections removed, of the lower right hand corner of the awning as viewed in Fig. 1, and showing details of construction, and

Fig. 8 is a fragmentary side elevation, partly in section, showing the manner in which the uppermost member of the supporting frame of the awning functions to retain the sections in proper position when such sections are in their extended positions.

Referring more in detail to the accompanying drawings, wherein like reference numerals have been employed to designate like parts throughout the several views, the numeral 1 designates, broadly, a rectangular window frame of any desired or preferred construction. At each side of the frame 1 there is attached a suitable frame 2 for supporting the awning and for guiding the slidably-connected awning sections to be herein-after described, the frame 2 preferably being constructed from flat metal stock which is readily bendable but which is sufficiently strong and rigid to perform its intended function. The upper end of each awning frame member 2 is rigidly attached to the upper, outer face of the window frame 1 by means of suitable screws or other fastenings 3 which pass through apertures in an up-

turned portion 4 bent to occupy a position parallel to the outer surface of the window frame 1. Each awning frame member 2 includes a portion 5 which extends downwardly and outwardly with respect to the window frame 1 for a suitable distance, and at a proper angle, which distance and angle are determined by the size of the window and the size of the awning to be employed, and is then bent rearwardly to form a horizontally extending portion 6, the inner end 7 of which is bent to occupy a position parallel to the plane of the window frame 1 and which bent portion is attached to the outer face of the side member of said window frame below the point of attachment of the upper portion 4 by means of suitable screws or other fastenings 8. A strip 9 preferably formed from flat metal stock, is associated with each awning frame 2 and has its lower end 10 bent downwardly as best shown in Fig. 6, and said lower end is attached to the upper surface of the inclined portion 5 of the awning frame by a bolt 11 which passes through the strip 9 and through the inclined portion 5 of the awning frame, the arrangement being such that the strip 9 is maintained in parallel, spaced relation with respect to the upper surface of the inclined portion 5. The upper end of the strip is bent upwardly as at 12, to occupy a position parallel to the upturned portion 4 of the awning frame, this upturned portion 12 being provided with an elongated slot 13 adapted to receive therethrough a screw 14 which passes through an aperture in upturned portion 4. The head of screw 14, or a suitable washer disposed beneath said head, overlies the outer face of the upturned portion 12, and the screw 14 is screwed into the window frame 1 only to a sufficient extent to cause said head or washer to bear lightly upon the outer surface of said upturned portion 12, whereby said end may be moved vertically for an extent determined by engagement between the shank of the screw 14 and the walls defining the ends of the slot 13.

The protective portion of my improved awning comprises a series of horizontally disposed, slidably connected sections formed of relatively rigid material, preferably relatively thin sheet metal. Each section comprises a flat horizontally disposed top portion 15 and depending, vertically disposed side portions 16. In the accompanying drawings I have illustrated an awning consisting of five of these sections which I have numbered 17, 18, 19, 20 and 21. The relative lengths of these sections 15 increase progressively from the lowermost section 17 to the uppermost section 21 so that these sections are slidable one within and beneath another, and the lengths of the depending, vertically disposed side portions 16 increase progressively from the lowermost section 17 to the uppermost section 21 so that the bottom edges of the several side portions will be disposed in the same horizontal plane when the said sections are in their extended positions. The intermediate sections 18, 19 and 20 are of like construction except for their progressively increasing lengths and the progressively increasing lengths of their depending side portions 16.

The uppermost section 21 is provided at the top thereof with an upstanding flange 22 which has vertical slots near its ends adapted to receive therethrough the screws 14 above referred to. The section 21 is placed on the top of the portion 5 of the spaced awning frames 2 and beneath the strip 9 with the slots in said section in alignment

with the slots 13 in strips 9. Screw 14 is then inserted through the aligned slots 13 and the slots in the upturned flange 22, and said screw is secured into the window frame 1 so that the head 5 of said screw or the washer positioned beneath said head bears lightly on the outer surface of the upturned portion 12 whereby said section 21 and said upturned portion 12 may partake of vertical movements.

10 The lowermost section 17 is provided at its outer edge with a depending front portion 23, the lower edge of which is cut or otherwise formed to simulate the scallops of a conventional canvas awning, and which front portion is of a length 15 which insures that its lower edge will be disposed in the same horizontal plane occupied by the lower curved edges of depending portions 16 of sections 18, 19, 20 and 21 when the sections are 20 in their extended positions. The depending portion 23 of section 17 is provided at each end thereof with a vertically extending slot 24 and with a cut-out portion 25, and lugs 26, having apertures 27 and 28 therein, are secured to the front face of said depending portion 23 by means 25 of screws 29 and overlie each of the cut-out portions 25, said lugs extending upwardly and above the upper surface 15 of the lowermost section 17. The width of slot 24 is slightly greater than the width of the awning frame member 5 so that the 30 section 17 is freely slidable along the length of said member.

Sections 17, 18, 19, 20 and 21 are slidably connected to each other by means of pin and slot connections comprising headed pins or rivets 30 mounted on each of the depending side portions 16 near the forward or outer edges thereof and disposed in elongated slots 31 cut through said depending portions 16, said slots extending substantially parallel to the member 5 of the awning 40 frame 2 and being staggered with respect to each other as clearly shown in Fig. 1. By virtue of this construction, it is possible to arrange the several sections so that the forward edge of an 45 upper adjacent section overlaps the rear edge of the next adjacent section, this overlapping arrangement being effected and maintained by the engagement between the shanks of the headed pins or rivets 30 and the walls defining the lower or outer ends of elongated slots 31. Since the 50 length of the sections progressively increase from section 17 to section 21, it is possible to move the sections together, one within and beneath another as best shown in Fig. 2, in which positions the headed pins or rivets will occupy positions 55 at the rear or inner ends of the slots 31, it being noted that the heads of said pins or rivets are relatively smooth and flat to permit this "nesting" of the said sections and the sliding of said sections within and beneath each other.

60 The preferred means for operating the sections of my improved awning, consists of a system of flexible cords, ropes, chains or the like, suitable pulleys, and suitable cleats. I have illustrated this preferred operating means in Figs. 5 and 6 of the accompanying drawings, from which it will be noted that a flexible element 32 has one end passed through the aperture 28 in the lug 26 at the right hand side of the awning as viewed in Fig. 5, the end of said element being knotted 65 adjacent the rear face of said lug. This element 32 is passed around pulley 33, then over pulley 34, then across the width of the awning and over pulley 35, then downwardly and upwardly to form the elongated, depending loop 36, then over pulley 37, then downwardly and around pulley 28, and

then through aperture 28 in the lug 26 at the left hand side of the awning as viewed in Fig. 5, the end of this flexible element 32 being knotted adjacent the rear face of said lug. A second flexible element 39 has one end passed through the aperture 27 in the lug 26 at the left hand side of the awning as viewed in Fig. 5, the end of said element being knotted adjacent the front face of said lug. This element 39 extends upwardly and then over pulley 40, then across the width of the awning and over pulley 41, then downwardly and upwardly to form the elongated, depending loop 42, then over pulley 43, then through aperture 27 in the lug 26 at the right hand side of the awning as viewed in Fig. 5, the end of this flexible element 39 being knotted adjacent the front face of said lug. Each of the elongated, depending loops 36 and 42, respectively, has the flexible elements thereof tied, knotted, or clipped together, as is usually the case with the flexible operating cords or loops of conventional awning, Venetian blind or like operating cords or loops, such knotting, tying, or clipping together insuring even operation of the awning by an even pull on the flexible elements constituting each of the said depending loops. Unless the elements constituting each loop 36 or 42 are knotted, or otherwise secured together, or unless the person raising or lowering the awning exerts an even and uniform pull on the flexible elements of each loop, it is sometimes difficult to obtain smooth and even operation of the awning. Suitable cleats 44 and 45 are secured on the outer face of the window frame 1, which cleats may have the loops 36 and 42 of the flexible elements wrapped therearound to maintain the sections of the awning in the desired "nesting," intermediate, or extended positions.

It is believed that the operation of my improved awning will be readily apparent from the foregoing description of the construction thereof. Suffice it to say that when the sections occupy their extended positions as illustrated in Fig. 1, and when it is desired to move said sections to the retracted, "nested" or non-shading position illustrated in Fig. 2, it is merely necessary to loosen loops 36 and 42 from their respective cleats and to pull downwardly on the depending loop 42. Such action on the part of the operator will cause the lowermost section 17 to slide upwardly along the inclined portions 5 of the awning frames at opposite sides of the window frame until the said lowermost section 17 slides beneath the next succeeding section 18, whereupon the lugs 26 will engage the lower edge of section 18 and will cause the sections 17 and 18 to slide beneath the next succeeding section 19. The lugs 26 will next engage the lower edge of section 19 and will cause the sections 17, 18 and 19 to slide beneath the next succeeding section 20, whereupon the lugs 26 will engage the lower edge of section 20 and will cause the sections 17, 18, 19 and 20 to slide beneath the uppermost section 21. The loops 36 and 42 are then wrapped around the cleats 45 and 44, respectively, to thus retain the sections of the awning in their retracted, "nested" or non-shading positions. As above stated, the flexible elements of loops 36 and 42 are preferably knotted or otherwise secured together, to insure even and uniform operation of each loop and, hence, uniform and even operation of the awning.

When it is desired to move the sections of the awning from their positions shown in Fig. 2 to their positions shown in Fig. 1, the loops 36 and 42 are disengaged from the cleats 45 and 44,

respectively, and the operator pulls downwardly on the depending loop 36 whereupon the sections will be moved downwardly along the inclined frame sections 5 to assume the positions shown in Fig. 1, the pin and slot connections between the several sections limiting this downward movement to insure a proper overlapping of the outer or forward edge of each section with respect to the inner or rear edge of the adjacent section.

When the sections are moved from the positions shown in Fig. 1 to the positions shown in Fig. 2, it will be noted that the upper ends of the strips 9 and the uppermost section 21 will be elevated to permit the underlying sections 17, 18, 19 and 20 to assume positions within and beneath the section 21, due to the elongated slots 13 in the upturned ends 12 of the strip 9 and the elongated slots in the upturned portion 22 of section 21, these upturned portions being freely slideable with respect to the screws 14. As clearly illustrated in the accompanying drawings, the strips 9 function as wind guards to prevent upward movement of the cooperating sections of the awning with respect to the supporting portions 5 of the awning frame members.

It will thus be seen that I have perfected an awning construction which adequately fulfills the objects of my present invention and which possesses many novel and desirable features of construction and operation over the awnings of the prior art. It will be obvious that by removing the strips 9, the sections 17, 18, 19, 20 and 21 may be readily lifted off of their supporting frames to be cleaned and/or painted. It will also be obvious that the entire awning and its supporting frame structure and accessories may be made of metal or other material or materials of a relatively indestructible nature and that it will not be necessary to remove the awning from the window during periods of the year when the use of an awning is unnecessary.

It is to be understood that numerous changes in the construction, and in the size, shape and arrangement of parts, may be resorted to without departing from the spirit of my present invention or from the scope of the subjoined claims. Many changes will suggest themselves to those skilled in the art. For example, it is not essential that the depending, vertically disposed side portions 15 be incorporated in the awning, as these side portions could be readily omitted and the pin and slot connection provided on the upper flat surfaces 15 of the sections.

A further possible modification which will suggest itself to one skilled in the art is the omission of the relatively long side flanges 16 and the substitution therefor of relatively short depending flanges of only a sufficient depth to accommodate the pin and slot connections between the several sections and to hold said sections against relative lateral displacement. It will be apparent from the foregoing description of construction and operation that the several sections of the awning may be adjusted to any desired intermediate position between the fully opened and fully closed positions above described, such sections being retained in their selectively adjustable positions by means of the operating ropes and cleats above referred to. Further, the loops 36 and 42 might extend through openings or passages provided in the window frame at the upper portions thereof, whereby the flexible operating members 32 and 39 would extend to the inside of the dwelling and adjacent the window frame, whereby the awning could be operated from the

inside of the window. It will also be obvious that arrangements of pulleys and flexible operating means other than the preferred form disclosed herein may be employed as the means for operating the awning.

Having thus described my invention, I claim:

1. An awning comprising a plurality of relatively flat, slidably connected sections, a frame member on which said sections are supported, a strip overlying the sections, and means for moving said sections relative to each other and along said frame member and beneath said strip, from a position wherein the sections are extended, to a position wherein the sections are superimposed.

2. An awning comprising a plurality of relatively flat, slidably connected sections, a frame member on which said sections are slidably supported, a strip overlying the sections and having one end attached to a fixed support for limited sliding movement on said support, and means for moving said sections relative to each other and along said frame member from a position wherein the sections are extended, to a position wherein the sections are superimposed, said strip overlying the upper surface of said sections when said sections are extended and overlying the uppermost section when said sections are superimposed, said strip being movable with respect to said frame to accommodate the plurality of sections between said frame and said strip when such sections are disposed in superimposed relation therebetween.

3. An awning comprising a plurality of relatively flat, slidably connected sections including an end section adapted to be secured to a substantially vertical supporting surface, a pin and slot connection between said end section and said supporting surface to provide for relative adjustment of said end section, a frame member secured to the supporting surface and underlying and supporting said sections, and means for moving the remaining sections along the frame member to positions beneath said end member, the pin and slot connection between said end member and the supporting surface permitting vertical movement of said end section whereby the remaining sections may be disposed between said end section and frame when the sections are arranged in superimposed relation.

4. An awning comprising a plurality of relatively flat, slidably connected sections adapted for movement from an extended position to a position wherein the sections are superimposed, and including an end section provided with a vertically extending, elongated slot; means passing through said slot for securing said end section to a substantially vertical support and permitting said end section to move vertically with respect to said support; a frame underlying the sections when said sections are in either superimposed or extended positions; a strip overlying the sections and frame and having an end portion provided with a vertically extending, elongated slot for engagement by the means which passes through the slot in the said end section

for securing the strip to said support and permitting vertical movement of the end portion of said strip, whereby said strip and end section may move vertically with respect to said support; and means for moving said sections other than said end section along the frame and beneath said strip from a position wherein the sections are extended, to a position wherein the sections are disposed in superimposed relation beneath said end section and strip.

5. An awning comprising a plurality of slidably connected sections each including a relatively flat top member and depending side portions, the lengths of said sections and depending portions progressively decreasing from the uppermost section to the lowermost section, and means for moving said sections relative to each other from a position wherein the sections are extended, to a position wherein the sections are nested one within the other, the lower edges of the depending side portions all lying in substantially the same horizontal plane when the sections are in their extended positions.

6. An awning comprising a plurality of slidably connected sections including an uppermost section secured to a vertical support, intermediate sections, and a lowermost section; a frame secured to the vertical support and including spaced outwardly and downwardly inclined members along which the intermediate and the lowermost sections are easily slidable; a depending flange portion extending along the outer edge of the lowermost section and having its lower edge disposed below the frame when the sections are in extended position, said depending flange portion having spaced slots therein to engage over said spaced members of said frame; and means for moving said lowermost and intermediate sections along said spaced members of said frame from a position wherein said sections are extended, to a position wherein they are superimposed beneath the uppermost section.

7. An awning comprising an uppermost section, intermediate sections and a lowermost section slidably connected together, each section including a top member and depending side portions, the lengths of said sections and depending side portions progressively decreasing from the uppermost section to the lowermost section; a frame having a downwardly and outwardly inclined portion along which said sections are freely slidable, the lower edges of the depending side portions of said sections all lying in substantially the same horizontal plane when the sections are in their extended positions; a depending flange extending along the outer edge of the lowermost section and having its lower edge in substantially the same horizontal plane occupied by the lower edges of the side portions of the sections when said sections are in their extended positions; and means for moving said sections relative to each other and along the inclined portion of the frame from a position wherein the sections are extended, to a position wherein the sections are nested one within the other.

HERMAN MASHMEYER.
